UNITED STATES PATENT OFFICE.

ARTHUR J. RAY, OF CHICAGO, ILLINOIS; FRED T. MADSEN, OF GREEN BAY, WISCONSIN; AND HERBERT F. OBERGFELL, OF RIVER FOREST, ILLINOIS, ASSIGNEES, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed January 11, 1921. Serial No. 436,559.

The present invention relates in general to automatic telephone systems, but is more particularly concerned with automatic telephone systems of the kind which are generally installed in small towns or villages, these systems being commonly known as "mixed service systems", or "community automatic exchanges". Reference is made here to the U. S. patent to Willis, No. 1,318,004, issued Oct. 7, 1919, on which this invention is an improvement.

The system herein described provides for giving local service to private or individual line subscribers and to rural or party line subscribers, and also provides means whereby such subscribers are given access to trunk lines extending either to an automatic exchange or to a manual exchange or both, one of the objects of the invention being the provision of an improved automatic connector switch for taking care of the different kinds of service named.

A further object of the invention is to provide a new and improved method of selectively signalling a large number of subscribers on a rural party line.

These and other objects of the invention will appear fully hereinafter.

Referring now to the drawings:

30 In Fig. 1 is shown an ordinary automatic substation A having a rotary lineswitch C individual thereto. The lineswitch C is of the well known rotary type, with its wipers moving in a forward direction only and having no normal position, and has the function of extending the line of substation A, when the receiver is removed, to a trunk line terminating in an idle "mixed service" connector.

40 These connectors are of the usual Strowger vertical and rotary type and have access to individual and party lines and also to trunk lines. One of these connectors is shown at H in the drawings. Associated with this connector are four minor switches I, J, K, and L, Fig. 2, which are simple rotary switches adapted to be rotated in response to impulses and restored to normal by the operation of their respective release magnets. At M in Fig. 2 is shown a code ringing machine which is common to the exchange, and which consists of a revolving drum having rows of metal contacts on it

which are adapted to be engaged by a number of wipers 275-281, inclusive. Around the outside of the drum are a number of projections which are arranged so as to engage the spring 297 and move it into contact at regular intervals with the contact 280'. This operation serves to ground the several rows of contacts on the drum. These projections are so placed that the ground is removed from the contacts while the brushes are still in engagement with them, which of course prevents the sparking which would otherwise occur were the brushes to make and break their own connections.

One of the individual lines to which the connector H has access is shown in Fig. 6, and one of the rural or party lines in Fig. 5.

Two trunk lines going to other exchanges are shown in Figs. 3 and 4, the one in Fig. 4, being a manual trunk terminating in a ring down signal and a jack, and the one in Fig. 3 being an automatic trunk line including a repeater of ordinary two wire construction.

Having briefly set forth and described the apparatus shown in the drawings, the operation of the system will now be described. For this purpose it will be assumed in the first case that an automatic private line subscriber at substation A desires to call the subscriber at substation A'. When the calling subscriber removes his receiver a circuit is completed over the line conductors 11 and 12 for the line relay 14 of the lineswitch C. Upon energizing, the line relay completes a circuit extending through the switching relay 13 and the stepping magnet 15 in series at its armature 20, and at its armature 19 connects the test wiper 26 to the above circuit at a point midway between the switching relay and the said stepping magnet. The operation now depends upon whether the test contact with which the test wiper 26 is in engagement is or is not busy. If this test contact is busy it will have ground potential upon it, the switching relay 13 will be short circuited, and the stepping magnet 15, which interrupts its own circuit, will operate as a buzzer to advance the switch wipers 25-27, inclusive, in search of an idle trunk line. This operation will continue as long as the test wiper 26 engages busy or grounded test contacts. However, we

may assume that in the present case when the call is initiated the connector H is idle and the test contact 31 thereof is not grounded. Under these circumstances when the line relay 14 is energized, the switching relay 13 is energized immediately afterwards, with the result that the line conductors 11 and 12 are disconnected from the winding of the line relay 14 and from ground, 10 respectively, and are extended by means of armatures 16 and 17, wipers 25, and 27, bank contacts 30 and 32, normally closed spring contacts controlled by relay 50, armatures 70 and 71, and through the upper and lower 15 windings of the line relay 52 of the connector H to battery and ground, respectively. Immediately upon the extension of the line as above described the line relay 52 energizes and closes the circuit of the slow acting release relay 53. Upon energizing, relay 53 prepares the circuit of the switch for operation in the usual manner, at its armature 80, and at armature 79 completes a holding circuit extending back to the lineswitch C over 20 the following path: ground G², working contact of armature 79 and the said armature, release trunk conductor 79', test contact 31, test wiper 26, armature 17 and its front contact, winding of switching relay 13, and the winding of the stepping magnet 15 to battery. It is understood that the above 25 circuit is established before the slow acting line relay 14 has had time to deenergize. By a ground potential on the test contact 31 and its multiples this holding circuit also serves to render the connector H busy to other lineswitches, and the busy potential also extends by way of the private normal conductor 34 to multiple test contacts in 30 the banks of all the connector switches, thereby protecting the line from intrusion in a well known manner.

Returning now to the operation of the connector H, when the subscriber at substation A operates his calling device S for the first digit of the desired number a series of interruptions are produced in the circuit of the line relay 52 which operates in response thereto and at each retraction of its armature 35 77 completes a circuit extending from ground G', back contact and armature 68, armature 77 and its back contact, armature 80 and its front contact, winding of slow acting relay 54, armature 104 and its back contact, armature 96 and its back contact, winding of the vertical magnet 126, conductor 186, first contact and wiper 267 of the minor switch J to battery. By the operation 40 of the vertical magnet 126 the wipers 135-138, inclusive, are raised step by step until they stand opposite the level of bank contacts in which is located the set of contacts associated with the line of the substation A'. The slow acting series relay 54 which is energized in series with the vertical magnet, maintains its armature attracted throughout the vertical movement of the switch. Upon the first vertical movement of the switch, the off normal springs 82 and 83 are shifted into their alternate position and 45 a circuit is thereby completed extending as follows: ground G³, off normal springs 83, armature 113 and its back contact, armature 86 and its front contact, and through the winding of the slow acting relay 59 to battery. Relay 59 is energized and being slow acting maintains its armatures attracted for a short interval after the deenergization of the slow acting series relay 54, which retracts its armatures an instant after the termination of the vertical movement of the switch. An impulse of current is then sent from ground G³, springs 83, armature 113 and its back contact, armature 86 and its front contact, back contact of armature 102 and the said armature, back contact and armature 94, conductor 184, and thence through the winding of the rotary magnet 252 of the minor switch J to battery. On energizing 50 magnet 252 rotates the wipers 267 and 268 of the minor switch into engagement with the second set of bank contacts.

The subscriber at substation A may now operate his calling device in accordance with 55 the second and in this case the final digit of the desired number. As before, a series of interruptions is produced in the line circuit to which the line relay 52 again responds by transmitting a series of impulses to the rotary magnet 127 over the following path: ground G', back contact and armature 68, armature 77 and its back contact, armature 80 and its front contact, through the winding of the slow acting series relay 54, armature 104 and its back contact, armature 96 and its back contact, through the winding of the rotary magnet 127, conductor 185, second contact engaged by wiper 267 and the said wiper to battery. Responsive to these 60 impulses the rotary magnet is operated to rotate the switch wipers into engagement with the particular set of bank contacts in which the line of substation A' terminates, these bank contacts being indicated in the drawing by the reference numerals 150, 151, 152, and 153. As before, the slow acting relay 54 is energized in series with the rotary magnet and completes the circuit of the slow acting relay 59. After the operation of the rotary 65 magnet 127, the slow acting relay 54 deenergizes. Relay 59 also prepares a testing circuit which is effective if the line of the subscriber at substation A' is busy. Supposing this to be the case, a ground potential will be present on the test contact engaged by the test wiper 137. A circuit is thereby completed extending as follows: from the said grounded test contact, test wiper 137, conductor 196, contact engaged by wiper 266 70

and the said wiper, conductor 180, armature 66 and its back contact, armature 85 and its back contact, armature 117 and its front contact, back contact and armature 98, and 5 thence through the winding of the test relay 57 to battery. Upon energizing the test relay establishes a locking circuit for itself at armature 105, and at armature 106 connects a lead from the busy machine to the lower 10 heavy talking conductor. By this means the calling subscriber is given an audible busy signal, and being advised thereby that the desired line is for the time being inaccessible, he will hang up his receiver.

Having described the operations which take place when the called line is busy, it will now be assumed that the line is idle when the connection is attempted. Under these circumstances, when the test wiper 137 comes into engagement with the ungrounded test contact 152, the test relay 57 will not be energized. Then when the slow acting relay 59 deenergizes at the end of the rotary movement of the switch, an impulse of current is again sent to stepping magnet 252 of the finder switch J to step the wipers 267 and 268 into engagement with the third set of bank contacts. A circuit will be completed for the switching relay 56 extending as follows: from the grounded release trunk conductor 79', armature 105 and its back contact, through the lower winding of the switching relay 56, back contact and armature 117, back contact and armature 85, back 25 contact and armature 66, conductor 180, wiper 266 and contact engaged thereby, conductor 196, test wiper 137, test contact 152, conductor 176, winding of the switching relay 14' and then through the winding of 30 the stepping magnet 15' to battery. Upon the closure of the above traced circuit, relays 56 and 14' energize in series, and the latter relay is operated to clear the line of the substation A' of its normal battery and ground connections in the line switch C². It is noted that relay 14' is operated only about half way, due to a mechanical interlocking device controlled by the line relay 16', which was not operated, and relay 35 14' does not therefore extend the line conductors through to its wipers. At the connector H, when the switching relay 56 energizes, the said relay establishes a locking circuit for itself at its armature 95, connects direct ground to the test wiper 137 at armature 97, opens the operating circuit of the minor switches associated with the connector at armature 96, and at armatures 94 and 100 completes the ringing circuit for the 40 called subscriber's telephone A'. Ringing current flows from the generator V, first contact and wiper 270, conductor 182, back contact and armature 91, armature 100 and its front contact, back contact and armature 69, wiper 138, bank contact engaged thereby and

thence over the lower line conductor 174, ringer and condenser of the substation A', back over the upper line conductor 172, bank contact 150, wiper 135, armature 65 and its back contact, armature 87 and its back contact, armature 109 and its back contact, lower winding of ring cut off relay 55, front contact and armature 94, conductor 184, and then through the winding of the stepping magnet 252 to battery. Magnet 252 does not 70 receive enough current to energize and relay 55 is so constructed that it does not respond to alternating current. As the drum of the ringing machine M rotates, the brush 281 engages the contact 287, and similar contacts, each time completing the circuit of relay 101 from the grounded contacts. As the contact 287 and similar contacts are equally spaced on the drum, this serves to interrupt the circuit for relay 101 at regular intervals, 75 which operates to intermittently apply ringing current to the above traced ringing circuit. Now when the called subscriber at substation A' answers, the ring cut off relay 55 will energize, a path for direct current being 80 provided through the transmitter and receiver of the called substation. Upon energizing, relay 55 establishes a locking circuit for itself at armature 89, opens the ringing circuit at armatures 87 and 91, and at the 85 working contacts of these armatures finally completes the talking connection.

The desired connection has now been established. The transmitter at the called substation A' is supplied with talking current 100 from the windings of the back bridge relay 51 which energizes and in the usual manner reverses the battery back to the calling subscriber who is supplied talking current from the windings of the line relay 52. The voice 105 currents take the path shown in heavy lines which will be understood without further explanation.

When the subscribers are through talking they will both replace their receivers. The 110 replacement of the receiver at substation A causes the lineswitch C and the connector H to be released in the following manner: When the line circuit of the line relay 52 is broken by the replacement of the receiver, 115 the line and release relays 52 and 53 are both deenergized, and a circuit is completed for the release magnet 128, extending from ground G', back contact and armature 68, armature 77 and its back contact, armature 80 and its back contact, off normal springs 82, back contact and armature 112, and through winding of the release magnet 128 to battery. Magnet 128 operates to restore the connector H to normal and at the same 120 time places ground on conductor 198 which extends through the winding of the release magnet 259 of the minor switch J to battery. Release magnets 288 and 261 of the minor switches I and K were energized in 125 130

multiple with the release magnet 128 of the connector H but since neither switch has been operated the energization of these magnets is without effect. The lineswitch C is restored to normal upon the deenergization of the release relay 53, ground being then removed from the holding circuit of relay 13. It will be noticed that an auxiliary release circuit is completed for the release magnets 128, 288, and 261 in multiple with the one above traced extending from ground G', back contact and armature 68, armature 77, armature 80 and its back contact, conductor 179, contact engaged by wiper 268 and the said wiper, conductor 195, back contact and armature 112, and thence through the winding of release magnets 128, 288 and 261. Thus the circuit of the release magnets of the various minor switches will not be opened when the connector H is restored to normal but rather when the minor switch J reaches normal thereby giving ample time for the release of all the switches.

The process of setting up a local connection when a private or individual line is called having been above explained, the manner in which a party line subscriber is called will now be described. All party line subscribers have four digit numbers and as before stated respond to code rings. The code ring of a particular station on a party line corresponds to the last two digits of that party line subscriber's number. For instance, let us suppose that the telephone number at substation A² is number 2631, in which case the subscriber will respond to the code: 3 short rings, pause, 1 short ring.

When the subscriber at substation A takes off his receiver preparatory to making the call, a circuit is completed for the line relay 14 of the lineswitch C in the usual manner over the line conductors 11 and 12 in series. Upon energizing, the line relay 14 closes at its armature 20 a circuit which includes the switching relay 13 and the stepping magnet 15 in series, and at its armature 19 connects the test wiper 26 to a point midway between the switching relay and the said stepping magnet. The operation now depends upon whether the trunk line with which the wipers 25-27, inclusive, are associated is busy or idle. If busy a ground potential will be present on the test contact engaged by the test wiper 26. The switching relay will therefore be short circuited and the stepping magnet 15 being supplied with direct ground will operate as a buzzer to advance the wipers 25-27, inclusive, step-by-step in search of an idle trunk line. It will be assumed, however, that the trunk line with which the wipers of the lineswitch C were associated with when a call was initiated is the trunk line shown in the drawings and is idle at this time. Under these conditions, upon the line relay 14 energizing, the switch-

ing relay, being no longer short circuited, will energize immediately afterwards in series with the stepping magnet 15. As a result of the energization of the switching relay, the line conductors 11 and 12 are disconnected from the winding of the line relay 14 and from ground, respectively, and extended by way of armatures 16 and 18 and their working contacts, wipers 25 and 27, bank contacts 30 and 32, normally closed contact springs controlled by relay 50, armatures 70 and 71 and their resting contacts to the upper and lower windings of the line relay 52 of the connector H. As before described the line relay 52 on energizing completes the circuit of the slow acting relay 53 which upon attracting its armature prepares the operating circuits of the connector H and at the same time establishes a holding circuit for the switching relay 13 of the lineswitch C. The calling subscriber may now operate his calling device S in accordance with the first digit of the desired number thereby producing a series of interruptions in the line circuit of the line relay 52. The line relay operates in the usual manner sending a corresponding series of impulses to the vertical magnet 126 in series with the slow acting relay 54. Magnet 126 operates to raise the wipers 135-138, inclusive, step-by-step until they are placed opposite the second level of bank contacts in which the desired party line is located. The slow acting series relay 54 energizes in series with the vertical magnet thereby completing the circuit of the slow acting relay 59. Upon the deenergization of the series relay, an impulse of current is sent from ground G³, off normal springs 83, armature 113 and its back contact, armature 86 and its back contact, armature 116 and its front contact, back contact and armature 102, back contact and armature 94, conductor 184, and through the winding of the rotary or stepping magnet 252 of the minor switch to battery. Magnet 252 operates to step the wipers 267 and 268 onto the second set of bank contacts. When the subscriber at substation A operates his calling device for the second digit another series of interruptions is produced in the circuit of the line relay 52 which operates in response thereto, this time sending a corresponding series of impulses to the rotary magnet 127. The slow acting series relay 54 energizes in series with the rotary magnet 127 and again completes the circuit of relay 59. As before, when relay 54 deenergizes, following the cessation of impulses to the rotary magnet, an impulse of current is sent to the stepping magnet 252 of the minor switch J which advances the wipers 267 and 268 into engagement with the third set of bank contacts. Magnet 127 operates to rotate the wipers 135-138, inclusive, on to the sixth set of bank contacts in which termi-

nates the desired party line and which, as shown in the drawings, are the bank contacts 155, 156, 157, and 158. It will be seen that the private normal conductor 173 of the lineswitch C' terminates in the bank contacts engaged by the test wiper 136. Therefore if the party line, upon which the subscriber at substation A² is located, should happen to be busy, a ground potential will be present on the bank contact 156. However, this will have no effect at the present time. The calling subscriber will now operate his calling device for the digit 3, this being the third digit in the number of the subscriber at substation A². At each retraction of its armature, the line relay 52 sends an impulse of current over the following path: ground G', back contact and armature 68, armature 77 and its back contact, armature 80 and its front contact, winding of slow acting relay 54, armature 104 and its back contact, armature 96 and its back contact, conductor 187, winding of magnet 254, contact engaged by wiper 267 and the said 25 wiper to battery. Magnet 254 responds to these impulses and steps the wipers 269 and 270 on to the fourth set of bank contacts in the minor switch K. By the operation of the slow acting relays 54 and 59, the stepping magnet 252 of the minor switch J is again energized and the wipers 267 and 268 are rotated into engagement with the fourth set of bank contacts. The calling subscriber may now send the last digit of the desired 30 number which in this case is the digit 1. The line relay operates as before and sends one impulse of current to the stepping magnet 251 of minor switch I over a circuit extending from ground G', back contact and armature 68, armature 77 and its back contact, armature 80 and its front contact, winding of the slow acting relay 54, armature 104 and its back contact, armature 96 and its back contact, conductor 187, winding of magnet 251, wiper 267 in the fourth position to battery. Magnet 251 operates to step the wipers 265 and 266 of the minor switch I into their second position. As before, the series relay 54 and also the slow acting relay 59 are energized and an impulse of current is again sent to the stepping magnet 252 of the minor switch J thereby stepping the wipers 267 and 268 into their fifth position. As before stated, when this line is busy, a ground potential will be present on the bank contact 156 engaged by the test wiper 136. Assuming this to be the case, then before the slow acting relay 59 has deenergized a circuit may be traced from the said grounded 55 test contact, test wiper 136, conductor 191, bank contact engaged by wiper 266 and the said wiper, conductor 180, armature 66 and its back contact, armature 85 and its back contact, armature 117 and its front contact, back contact and armature 98, and through the winding of the test relay 57 to battery. Upon energizing relay 57 establishes a locking circuit for itself at armature 105 and applies the busy tone at armature 106 to the lower heavy talking conductor. When the 70 calling subscriber hears this tone, he will know that for the present the line of the subscriber at substation A² is inaccessible and he will replace his receiver, thereby causing the release of the connector and its 75 associated minor switches to be released in the manner hereinbefore described.

Having described the operation of the connector H and its associated apparatus when the line of the called subscriber at substation A² was busy, it will now be assumed that the line of the subscriber at substation A² was idle when the connection thereto was attempted. Under these conditions no ground will be present on the test contact 156 and following the deenergization of the slow acting relay 59, a circuit may be traced over the following path: ground on release trunk conductor 92, armature 105 and its back contact, lower winding of switching relay 56, back contact and armature 117, back contact and armature 85, back contact and armature 66, conductor 180, wiper 266 and the second bank contact, conductor 191, test wiper 136, bank contact 156, private normal conductor 173, winding of switching relay 14² and the winding of the stepping magnet 15² to battery. Relays 56 and 14² operate over this circuit. However, due to a mechanical device controlled by the line relay 16², the relay 14² 100 operates only far enough to clear the line conductors of their normal battery and ground connections. Upon energizing, relay 56 establishes a locking circuit for itself at armature 95, opens the operating circuits of the minor switch I at armature 96, places ground on the test wiper 136 at armature 97 in order to protect the line of the subscriber at substation A² from intrusion, and also 105 prepares the ringing circuit for the subscriber at substation A². When the switching relay 56 energizes, a tone from the tone machine T' flows over the following circuit: tone machine T', conductor 199, back contact and armature 121, conductor 197, fourth 110 contact and wiper 270, conductor 182, back contact and armature 91, armature 100 and its front contact, back contact and armature 69, wiper 138 and thence over the party line 115 on which the substation A² is located. This tone will be audible to any subscriber on the party line should he remove his receiver during a silent period between code rings informing him that the line is in use and he 120 will therefore replace his receiver upon the switchhook. The ring will not be cut off at this time for the reason that upon removing the receiver it rises only far enough to close the springs similar to 287' and 289' on account of the stop 288', and the subscriber's 125 130

receiver will be connected across the line through a condenser enabling him to know whether the line is or is not busy at this time without disturbing any of the operations.

- 5 It will be seen that the brushes 277 and 278 of the ringing interrupter M were selected by the last two digits called. Therefore, upon the termination of the last impulse and when the brush 277 engages the grounded contact 285, a circuit is completed extending as follows: grounded contact 285, brush 277, contact and wiper 269 of the minor switch K, conductor 181, back contact and armature 90, conductor 183, first contact and wiper 272 of the minor switch L, winding of stepping magnet 253, contact engaged by wiper 267 and the said wiper to battery. Magnet 253 operates to step the wipers 271 and 272 one step and at the same time closes at springs 286 a locking circuit for itself which extends to the spring 280' which was grounded at the same time the contact 285 was grounded. Therefore the stepping magnet 253 remains energized until the drum of the interrupter M rotates enough to allow the spring 297' to break contact with the spring 280'. When the wipers 271 and 272 are rotated one step, a circuit is completed extending as follows: ground G², off normal springs 83, conductor 194, wiper 271, conductor 190, and through the winding of relay 58 to battery. Upon energizing, relay 58 prepares the circuit for the ringing relay 60 which is energized intermittently by the operation of the interrupter M over the following circuit: grounded contacts 290 and 291, etc., brush 280, conductor 189, front contact and armature 111, and thence through the winding of relay 60 to battery. Relay 60, on energizing, completes the ringing circuit which extends from the ungrounded pole of generator V' by way of front contact and armature 121, conductor 197, contact engaged by the wiper 270 and the said wiper, conductor 182, back contact and armature 91, armature 100 and its front contact, back contact and armature 69, wiper 138, bank contact 158, conductor 177 and thence over the party line on which the subscriber at substation A² is located through the ringers and condensers of the substations on the said party line, conductor 175, bank contact 155, wiper 135, armature 65 and its back contact, armature 87 and its back contact, armature 109 and its front contact, and thence to ground on release trunk conductor 93. Relay 60 is momentarily energized each time one of the contacts 290, 291, and 292 passes under the brush 280, after which there is an interval, determined by the space between contact 292 and the next contact 293, during which relay 60 does not energize. This space is provided for the purpose of giving the usual interval between successive rings in the same code.

65 During the above mentioned interval, con-

tact 295 is moved into engagement with the corresponding brush 275, whereupon a circuit is again completed for the stepping magnet 253 by way of the second contact in the bank of wiper 272 and said wiper. Magnet 70 253 thereupon operates as before and steps the wipers 271 and 272 of the minor switch L into engagement with the third set of bank contacts. This operation occurs, it will be noted, during the silent period between 75 two successive rings, and its result is that the wiper 272 is connected up with the stop wiper 265 of the switch I so as to enable the second ring to be terminated, as will be explained subsequently. 80

At the end of the space between successive rings or just after the wipers 271 and 272 of the switch L have been advanced into engagement with their third set of bank contacts, the contact 293 passes under the brush 280, thereby giving one short ring in the above described manner. It will thus be seen that the code 3 short rings, pause, 1 short ring has been transmitted to the party line on which the subscriber at substation A² is 90 located. When the brush 276 engages contact 297, a circuit is completed extending from grounded contact 297 by way of brush 277, contact engaged by wiper 265 and the said wiper, wiper 272 in its third position, 95 winding of the stepping magnet 253, and wiper 267 in its fifth position to battery. Magnet 253 operates as before to advance the wipers 271 and 272 into their fourth position thereby breaking the circuit of relay 58 100 which immediately deenergizes opening the circuit to the ringing relay 60 at armature 111. When the brush 275 engages grounded contact 295 magnet 253 is again energized and steps the wipers 271 and 272 into their 105 fifth position thereby completing a circuit which extends as follows: ground G², off normal springs 83, conductor 194, wiper 271, conductor 193, and thence through the winding of the slow acting relay 59 to battery. Upon energizing relay 59 completes a circuit extending from ground G², off normal springs 83, armature 113, and its back contact, armature 86 and its back contact, armature 116 and its front contact, conductor 192, 110 and thence through the winding of the release magnet 260 of the minor switch L to battery. Magnet 260 operates to restore the wipers 271 and 272 into their first or initial position. 115

The lay out of all contacts on the drum of the ringing interrupter M is shown in the drawing, and hence the ringing operation will start in as before described upon the brush 277 again engaging the contact 285, the minor switch L being now in its normal position, and therefore the code ring of the subscriber at substation A² will again start as above explained. Should the subscriber at substation A² upon hearing his code call 120 125 130

remove his receiver in the middle of the code H when a calling subscriber desires to call a manual subscriber in a neighboring exchange. The subscriber at the substation A who desires to connect with the manual exchange will therefore remove his receiver and operate his calling device S in accordance with the digits 91. When the receiver is removed the lineswitch C operates as before described to extend the associated line to a trunk line terminating in an idle connector which we will assume is connector H. When the connection is thus extended, the line release relays 52 and 53 are energized as previously described and with the same results. When the calling device is operated the switch wipers 135-138, inclusive, are raised step by step by the vertical magnet 126 under control of the line relay 52 and are brought to rest opposite the ninth level, all in a manner previously explained. When the wipers are raised to the ninth level, the shaft controlled springs 124, are brought into engagement with each other by the operation of the shaft. This may be accomplished by any suitable cam arrangement. The springs 75 are also shaft springs but they are adjusted to be shifted by the shaft when it is operated to the tenth level. The springs 124 are also operated on the tenth level. A convenient way to mount these springs is just above the top of the shaft so that the springs 124 may be actuated by the circular cup spring casing which is mounted at the upper extremity of the switch shaft. To proceed, the slow acting series relay 54 is energized during the vertical movement of the switch and for an instant thereafter, and as before completes the circuit of the slow acting relay 59. On de-energizing, the relay 54 sends an impulse of current to the stepping magnet 252 of the minor switch J which operates to move the wipers 267 and 268 into their second position. When the next digit 1 is sent by the subscriber at substation A the line relay 52 operates as before and sends one impulse of current to the rotary magnet 127 in series with the slow acting relay 54. Magnet 127 operates to rotate the wipers 135-138, inclusive, into engagement with the first set of contacts in the ninth level. Relay 54 operates as before and completes the circuit of the slow acting relay 59. It will be noticed that two test wipers 136 and 137 are shown in the drawings each adapted to engage test contacts. In Fig. 7 one level of these test contacts are shown which we will assume represent the connections between the two sets of test contacts in the ninth level. It is assumed that in the case about to be described, there are a number of trunk lines going to a manual exchange. The connector H must be able to select and connect with an idle one of these trunks or, if all should be busy, notify the calling subscriber of this

When the code is finished relay 58 deenergizes, and if the receiver of the substation A² is removed and the trip 288' is moved to allow the receiver hook to engage both upper contacts, direct current will flow over a circuit extending from ground G⁷ on conductor 199 by way of back contact and armature 121, conductor 197, wiper 270 in its fourth position, conductor 182, back contact and armature 91, armature 100 and its front contact, back contact and armature 69, wiper 138, bank contact 158, conductor 177, through the switchhook springs transmitter and primary winding of the induction coil of the substation A², conductor 175, bank contact 155, wiper 135, armature 65 and its back contact, armature 87 and its back contact, armature 109 and its back contact, lower winding of ring cut off relay, front contact and armature 94, conductor 184, winding of magnet 252 to battery. Relay 55, while it does not respond to alternating current, energizes over this circuit. Upon energizing, relay 55 locks itself energized at armature 89, and at armatures 87 and 91 opens the ringing circuit, and at the front contacts of these armatures completes the circuit for the back bridge relay 51. This latter relay operates as before described to reverse the battery over the line of the calling subscriber at substation A for any well known purpose. Relay 55 on energizing also opens the initial operating circuit of the minor switch L. Conversation may now be carried on between the subscribers at substations A and A², battery being supplied to the calling subscriber from the line relay 52 and to the called subscriber from the back bridge relay 61. When the conversation is terminated, the release of the connector and its associated minor switches takes place in a manner heretofore described upon the subscriber at substation A replacing his receiver on the switchhook.

Having described how both party and straight line connections are set up, let us now consider the operation of the connector

- fact. For this purpose the test contacts of each trunk line except the last are tied together and those of the last trunk line of a group being left open. Thus as may be seen from Fig. 7 if the lower test contact of any one of the first trunks should be grounded, as is the case when one is busy, this ground will also be present on the upper test contact while in the case of the last contact of a group ground will only be present on the lower test contact. From the above it will be seen that both ordinary individual and party lines have their test contacts left untied. To proceed with the explanation of the present connection, should this first trunk line be busy, ground will be present on the test contacts engaged by both test wipers 136 and 137. A circuit may then be traced from ground on test wiper 137, conductor 196, wiper 266, conductor 180, armature 66 and its back contact, armature 85 and its back contact, armature 117 and its front contact, back contact and armature 98, winding of the test relay 57 to battery. On energizing, relay 57 opens the circuit to the stepping magnet 252 of the minor switch J at armature 102, and at armature 103 a circuit is completed from ground on the test wiper 136 by way of shaft controlled springs 124, front contact and armature 115, armature 103 and its front contact, back contact and armature 131, winding of relay 60 to battery. Upon relay 60 energizing, a circuit is completed extending from ground G³, off normal springs 83, armature 113 and its back contact, where it then divides, one circuit extending by way of armature 119 and its front contact, then through the winding of rotary magnet 127, conductor 185 and wiper 267 in its second position to battery, while the other circuit extends by way of armature 120 and its front contact through the winding of the slow acting relay 59 to battery. Magnet 127 operates to rotate the wipers 135-138, inclusive, onto the next set of bank contacts. If the trunk line which terminates in this set of bank contacts should be busy, ground will again be present on the test contacts engaged by the test wipers 136 and 137. As relay 59 is maintained energized, the relays 57 and 60 will again operate and the switch will continue to rotate until an idle trunk is found or the last trunk line in the group is found busy. In this latter case there will be no circuit for the energization of relay 60, and relay 57 will operate to give the busy tone to the calling subscriber. However, it will be assumed in the present case that the trunk line terminating in the bank contacts 145-148, inclusive, is the first idle trunk line. Under these circumstances following the deenergization of relay 59, a circuit is completed extending as follows: ground on release trunk conductor 92, armature 105 and its back contact, lower winding of relay 56, back contact and armature 117, back contact and armature 85, back contact and armature 66, conductor 180, wiper 266, conductor 196, wiper 137, bank contact 147, and resistance R' to battery. Relay 56 energizes, locks itself energized at armature 95 and prepares the ringing circuit in the same manner as herein explained in the first connection described. Ringing current now flows over a circuit extending from generator V, wiper 270, conductor 182, back contact and armature 91, front contact and armature 100, back contact and armature 69, wiper 138, bank contact 148, conductor 169, through the condenser and upper winding of the alternating current relay 300, armature 306 and its back contact, conductor 168, bank contact 145, wiper 135, armature 65 and its back contact, armature 87 and its back contact, armature 109 and its back contact, lower winding of the ring cut off relay 68, front contact and armature 94, conductor 184, and through the winding of magnet 252 to battery. Relay 300 being an alternating current relay responds to the ringing current, establishes a locking circuit for itself at armature 304, and at armature 303 lights the visual signal before the operator in the manual exchange. When the operator notices this signal she will insert the plug of her cord circuit into the jack J' thereby completing the circuit of relay 301 which opens the locking circuit of relay 300 and also providing a path for direct current through the ring cut off relay 55 which energizes cutting off the ring and completing the talking circuit. The cord circuit of the operator may be of any well known construction. After ascertaining the number desired by the subscriber at substation A the operator may extend the connection in accordance with well known manual practice. When the connection is completed and after finishing the conversation, the subscriber at substation A by replacing his receiver upon the switchhook causes the release of the connector H and lineswitch C and at the same time the operator is notified of the fact by the operation of a supervisory signal in her cord circuit, all in the usual manner.
- The explanation of the manner in which a trunk connection to an automatic exchange is established may now be proceeded with. As mentioned before the trunk lines going to the automatic exchange terminate in the tenth level. Therefore in order to connect to a trunk line going to the main exchange the calling subscriber will have to dial the number 01. Upon removing his receiver the lineswitch operates as before to select an idle trunk line leading to a connector switch which it will be assumed is the connector H. When the line is thus extended, the line release relays 52 and 53 energizes as before
- 125 130

with the same results. Upon the subscriber at substation A operating his calling device in accordance with the digit 0, ten interruptions are thereby produced in the circuit of the line relay 52 which responds thereto sending ten impulses of current to the vertical magnet 126 in series with the slow acting relay 54. Relays 54 and 59 operate as before sending an impulse of current to the stepping magnet 252. The vertical magnet 126 operates to step the wipers 135-138, inclusive, opposite the tenth level of bank contacts. Upon the tenth vertical step, the shaft controlled springs 124 and 75 are shifted into their alternate position. When the subscriber at substation A operates his calling device S in accordance with the next digit of his number, namely the digit 1, the line relay 51 operates in response thereto and sends one impulse of current to the rotary magnet 127. Slow acting relays 54 and 59 energize and if the trunk line with which the wipers are now in engagement is busy, ground will be present on the test contacts thereof engaged by the test wipers 136 and 137. The connector H will operate as before described to find an idle trunk or, if all trunks are busy going to this particular automatic exchange, it will stop rotating on the contacts in which the last trunk line of a group is terminated and transmit a busy signal to the calling subscriber at substation A. It will of course be understood that the test contacts of each group of trunk lines are connected in a manner similar hereinbefore described with regard to the ninth level. However, it will be assumed that the trunk line shown in the drawings comprising conductors 164, 165 and 166 is idle. Under these conditions, upon the test wipers 136 and 137 engaging contacts 141 and 142 and no ground being present thereupon, the switching relay 56 will energize. All this occurs in a manner similar to that hereinbefore explained. When relay 56 energizes, it establishes a locking circuit for itself at armature 95 and at the same time completes a circuit extending from ground on release trunk conductor 81 by way of armature 95, its front contact, shaft controlled springs 75, and the winding of relay 50 to battery. Relay 50 on energizing locks itself to ground on the release trunk conductor 92 and extends the line conductors 11 and 12 by way of armatures 65 and 69 and their front contacts, wipers 135 and 138, bank contacts 140 and 143, conductors 164 and 166, normally closed springs controlled by relay 325, and thence to the upper and lower windings of the line relay 326 which energizes completing the circuit of the slow release relay 327. Relay 327 energizes, removes battery from the release trunk conductor 165, and at armature 331 and its front contact places ground thereon, over which it flows by way of bank

contact 142, test wiper 137, conductor 196, wiper 266, conductor 180, armature 66 and its front contact, front contact and armature 67, winding of relay 50 to battery. This ground also extends back to the lineswitch 70 C and hence maintains switches C and H in their operated position. It will be understood that the above traced holding circuit is established before the slow acting release relay 53 deenergizes. The subscriber may now operate his calling device in accordance with the first digit of the subscriber's number in the distant automatic exchange. A series of interruptions is produced in the circuit of the line relay 326. Relay 326 80 on operating in response to these impulses breaks the bridge across the trunk conductors 340 and 341 a corresponding number of times thereby repeating the impulses sent to the line relay of the switch in the distant 85 exchange. This bridge across the trunk may be traced from trunk conductor 340, front contact and armature 333, armature 334 and its front contact, front contact and armature 336, trunk conductor 341. The 90 connection to the subscriber in the distant automatic exchange may now be completed in the ordinary manner.

It will be seen that this connector may have access to groups of trunks going to a 95 number of manual and automatic exchanges and because two digits are sent to the connector it will be unnecessary to allot one level to one exchange.

Having fully described and ascertained the features of our invention what we consider to be new and desire to have protected by Letters Patent will be pointed out in the appended claims.

What we claim as our invention is:

1. In a telephone system, a line, a connector switch, auxiliary switches individual thereto, means for establishing a connection with said line by means of said connector switch, code ringing mechanism, means for selectively operating two of said auxiliary switches in succession to select a particular code ring, and automatic means for operating another of said auxiliary switches to initiate the application of said code ring to 115 said line.
2. In a telephone system, a line, a connector switch, auxiliary switches individual thereto, a relay in said connector switch for applying ringing current to a called line, a code ringing interrupter, means for operating said connector to establish a connection with the said line, means for then selectively operating two of said auxiliary switches in 120 succession to select a code, automatic means for operating another of said auxiliary switches to prepare the circuit of said relay, and means for variably energizing said relay by means of said interrupter to apply 125 a code ring to said line.

3. In a telephone system, a line, a connector switch, auxiliary switches individual thereto, a relay in said connector switch for applying ringing current to a called line, a code ringing interrupter, means for operating said connector to establish a connection with the said line, means for then operating two of said auxiliary switches to select a code, automatic means for operating another of said auxiliary switches to prepare the circuit of said relay, means for variably energizing said relay by means of said interrupter to apply a code ring to said line, means operative upon the called subscriber answering for cutting off the ringing current from said line, and means effective if the called subscriber removes his receiver during a code ringing period for rendering the said ring cut off means inoperative.
4. In a telephone system calling and called subscribers, an automatic connector switch, auxiliary switches individual thereto, a relay in said connector switch for applying ringing current to a called line, means where by one of the calling subscribers may establish a connection with a called subscriber by means of said connector switch, a code ringing interrupter, means for then operating one of said auxiliary switches to select a code, automatic means for operating another of said auxiliary switches to prepare the circuit of said relay, means for variably energizing said relay by means of said interrupter to apply a code ring to said line, means under the control of said calling subscriber for releasing said connector switch, and means for rendering the said releasing means inoperative during a code ringing period.
5. In a code ringing machine, rows of variably positioned contacts, brushes cooperating with said rows, two directively controlled switches successively operated to select two of said brushes, a ringing relay and means for energizing it a plurality of times, the number of times depending on the brush selected by the first operated switch, a third switch and means for operating it to shift the control of said relay to the brush selected by the second operated switch, and means for then energizing said relay a plurality of times under control of the said last brush.
6. In a telephone system, two classes of subscribers' lines, cut off relays and private normal conductors associated with said lines, a connector switch having bank contacts in which the said conductors terminate, a private wiper in said connector adapted to engage only the said contacts associated with the lines in one class, another private wiper in said connector adapted to engage only the said contacts associated with the lines in the other class, means for operating said connector to select a called line in either class, two kinds of ringing equipment associated with said connector, and means under control of said wipers for putting one or the other of said equipments in use depending on the class in which the called line belongs.
7. In a telephone system, two classes of subscribers' lines, cut off relays and private normal conductors associated with said lines, a connector switch having bank contacts in which the said conductors terminate, a private wiper in said connector adapted to engage only the said contacts associated with the lines in one class, another private wiper in said connector adapted to engage only the said contacts associated with the lines in the other class, means for operating said connector to select a called line in either class, and means controlled over one of said wipers for signalling the called line immediately if said line belongs to one of said classes and controlled over the other of said wipers to signal the called line only after an interval if said line belongs to the other of said classes.
8. In a telephone system, two classes of subscribers' lines, cut off relays and private normal conductors associated with the said lines, a connector switch having bank contacts in which the said conductors terminate, a private wiper in said connector adapted to engage only the said contacts associated with the lines in one class, another private wiper in said connector adapted to engage only the said contacts associated with the lines in the other class, means for operating said connector to select a called line in either class, and a switching relay in said connector energized at once over one of said wipers if the called line belongs to one of said classes and energized after a time interval over the other of said wipers if the called line belongs to the other of said classes.
9. In a telephone system, private or individual lines and party lines, an automatic connector switch responsive to the calling of two digits in desired telephone numbers to select desired ones of said lines, means for automatically completing the connection and for signalling the called subscriber if the called line is a private line, means whereby the completion of the connection is deferred if the called line is a party line, code selecting mechanism responsive to another digit in the called number if the called line is a party line, and means for automatically completing the connection when the proper code is selected and for signalling the called subscriber in accordance with the selected code.
10. In a telephone system, two classes of lines, two digit telephone numbers assigned to the lines of one class, four digit numbers assigned to the lines in the other class, an automatic connector switch responsive to the calling of a two digit number to call a subscriber on a line in the first class and re-

sponsive to the calling of a four digit number to call a subscriber on a line in the second class, and ringing equipment automatically started in each case when the calling of the number is completed to signal the called subscriber.

11. In a telephone system, private or individual lines and party lines, an automatic connector switch, means whereby a calling subscriber can operate said connector in accordance with desired telephone numbers to connect with desired ones of said lines, and ringing equipment automatically responsive after two digits have been called to signal the called subscriber in case such subscriber has a private line, and automatically responsive after four digits have been called to signal the called subscriber in case such subscriber is on a party line.
12. In a telephone system, a trunk line extending to an automatic exchange, a trunk line extending to a manual exchange, a party line, an individual line, an automatic connector switch operable to establish connection with any one of said lines as a called line, means for closing a metallic connection through said connector in case the said automatic trunk line is connected with to permit the transmission of operating impulses, condensers included in the connection when any other line is connected with, means for transmitting signalling current over the manual trunk when the same is connected with, code ringing mechanism for signalling a desired party on said party line when the said party line is connected with, and automatic intermittent ringing equipment for signalling the party on said individual line when connection thereto is established.
13. The combination, with a ringing relay and an impulse sender for transmitting series of code impulses to said relay, of a plurality of progressively movable switches for registering digits in a called number, and a progressively movable sequence switch for placing said sender under the control of said register switches successively.

14. The combination, with a ringing relay, of a code ringing machine for operating said relay in accordance with two digit codes, said machine comprising a drum interrupter having two series of contacts arranged in line, a brush for engaging all said contacts in succession, a circuit including said relay and brush, and means for rendering said circuit effective after said brush has engaged a variable number of contacts in the first series of said contacts, and for rendering said circuit ineffective after said brush has engaged a variable number of contacts in the other series of contacts.

15. The combination, with a ringing relay, of a code ringing machine for operating said relay in accordance with two digit codes, said machine comprising a drum in-

terrupter having contacts, a brush for engaging all of said contacts in succession, a circuit including said relay and said brush, means for rendering said circuit effective after said brush has engaged a variable number of said contacts, and means for rendering said circuit ineffective after said brush has engaged the desired number of said contacts while said circuit is effective.

16. In a telephone system, a party line connector having primary and secondary motor magnets, two auxiliary ringing current selecting switches individual to said connector, each ringing switch having a motor magnet, a line relay in said connector, and another auxiliary switch individual to said connector for placing said magnets successively under the control of said relay.

17. In a telephone system, a party line connector having primary and secondary motor magnets, two auxiliary ringing current selecting switches individual to said connector, each ringing switch having a motor magnet, a line relay in said connector, another auxiliary switch individual to said connector for placing said magnets successively under the control of said relay, a conductor over which the said line relay controls the said magnets, a motor magnet for said last mentioned switch, and a relay included in said conductor for controlling said last mentioned magnet.

18. In a telephone system, a group of connectors, individual and party lines accessible to all said connectors, a common relay for use by any connector in ringing individual lines only, and an individual relay in each connector for ringing party lines.

19. In a telephone system, a combined individual and party line connector, individual ringing equipment and party line ringing equipment associated with said connector, means automatically responsive to the completion of a connection with an individual line for rendering the individual ringing equipment effective, and means automatically responsive to the completion of a connection with a party line for rendering said party line ringing equipment effective.

20. In a telephone system, a combined individual and party line connector switch, said switch having facilities for performing different characteristic ringing operations depending on the kind of line connected with, and means in said switch automatically responsive when a line is connected with for determining the character of the ensuing ringing operation.

21. In a telephone system, a combined individual and party line connector having two test wipers, individual and party lines accessible to said connector, private normal conductors for the individual lines terminating in the bank of one of said wipers, and

- private normal conductors for the party lines terminating in the bank of the other of said wipers.
22. In a telephone system, a combined individual and party line connector having two test wipers, individual and party lines accessible to said connector, a cut-off relay for each individual line controlled by one of said wipers, and a cut-off relay for each party line controlled by the other of said wipers.
23. In a telephone system, a connector having a test wiper, a test relay, an auxiliary ringing current selecting switch individual to said connector, and a circuit for said relay including said test wiper, and a wiper of said selecting switch.
24. In a telephone system, a connector switch for establishing connections with individual or party lines, said individual and party lines promiscuously interspersed with respect to each other in the bank of said switch, said switch having facilities for performing different characteristic ringing operations depending on the kind of line connected with, and means in said switch automatically responsive when a line is connected with for determining the character of the ensuing ringing operation.
25. In a telephone system, an automatic switch, a party line, a plurality of signalling means, means for indicating the busy or idle condition of said line, means for first operating said switch to connect to said line, means for then selecting any one of said signalling means, means for testing said line for the busy or idle condition, and means for maintaining said testing means disabled until after the selection of signalling means is completed.
26. In a telephone system, an automatic switch, an auxiliary switch associated with said automatic switch, a party line, a plurality of code signalling means, means for operating said automatic switch to connect to said line and for then operating said auxiliary switch to select any one of said code signalling means, means for testing said line for busy or idle condition operable only after operation of said auxiliary switch, and means for starting the signalling operation when the selected signalling means reaches its starting position provided the said party line is idle.
27. In a telephone system, an automatic switch, two auxiliary switches associated with said automatic switch, a party line, a plurality of signalling means, means for operating said automatic switch to connect to said line and for then successively operating said auxiliary switches to select any one of said signalling means, means for testing said line, and means for delaying the testing of said line until after said auxiliary switches are operated.
28. In a telephone system, an automatic switch, a party line, a code ringing mechanism, means for operating said switch to connect with said line, means for selecting a code for signalling a desired party on said line, means for testing said line, and means for maintaining said testing means disabled until the code is selected.
29. In a telephone system, signalling mechanism, a party line, means for connecting with said line, a first and second register for registering two digits of the party line number, means including a wiper of said first register to start the sending of signals over said line, and means including a wiper of said second register to stop the sending of signals over said line.
30. In a telephone system, a party line connector, signalling mechanism, a first and a second register individual to said connector, means for setting said registers in accordance with two digits of a called line, means including a wiper of said first register for starting the sending of signals, and means including a wiper of the second register for stopping the sending of signals.
31. In a control system, an impulse sender, a first and a second register, means for setting each register separately, means including a wiper of said first register for starting the sending of impulses, and means including a wiper of said second register for stopping the sending of impulses.
32. In a control system, an impulse sender, a first and second register, means for setting said registers separately, means including a wiper of said first register for starting the sending of a series of impulses in accordance with the setting of the first register, automatic means for starting the sending of a second series of impulses, and means including a wiper of said second register for stopping the sending of said second series of impulses in accordance with the setting of the second register.
33. In a telephone system, a party line connector, a party line, means for operating said connector to connect with said line, a signalling mechanism, a first and second register, means for setting said registers in accordance with two digits, respectively, of a line number, means including a wiper of said first register for starting the sending of a first series of signals over said line in accordance with one of said digits, automatic means for starting the sending of a second series of signals over said line, and means including a wiper of said second register for stopping the sending of said second series of signals in accordance with the other of said digits.
34. In a code signalling machine, means for sending two spaced series of impulses, and means for varying the number of effective impulses in each series while maintain-

ing the spacing between the series invariable, said means comprising a device for cancelling one or more impulses at the beginning of the first series and a second device for cancelling one or more impulses at the end of the second series.

35. In a telephone system, an automatic switch, a party line, means for operating said switch to connect with said party line, signalling selecting means operable in accordance with a plurality of digits after said switch is operated, and means for test-

ing said party line after said signalling selecting means is operated.
